WIRE SCREEN

Eldridge P. Douglass, Fayetteville, Ark.

Application April 28, 1937, Serial No. 139,372

2 Claims. (Cl. 139—425)

This invention relates to improvements in wire screen and to articles made from such wire.

The objects of the invention are primarily to make a wire screen which, when used in connection with an enclosing or supporting frame, will stiffen and brace the frame against distortion, and to make a wire screen of this nature which is capable of being manufactured by the use of weaving machinery, such as is now used for making wire screen, with modifications which are possible without entirely redesigning such machinery.

In the manufacture of screen wire at the present time continuous longitudinal or warp wires of sufficient number to form, at a chosen spacing, the desired width of screen are crossed and interwoven with woof wires, usually at the same spacing, these woof wires being substantially at right angles to the warp wires, the screen being made by machinery somewhat similar to that used in making cloth. The wire screen so made is in a continuous strip which is wound into a roll from which such lengths as are desired are cut for use. A length so cut is secured by nailing, clamping, or otherwise, along its edges to a frame which surrounds it. Obviously these frames may be of any shape but in the great majority of cases they are rectangular, and in the interest of economy the warp and woof wires of the screen are parallel to the side and end members of the frame. A wire screen so placed obviously affords no resistance to the frame to prevent distortion from rectangular shape. It immediately appears obvious that the wire screen might be so shifted that the wires would lie diagonally with respect to the sides and ends of the frame and would accomplish the bracing of such frame, which is much to be desired, but the obvious waste in using screen-wire in this manner is so great that it is substantially never resorted to. Applicant, therefore, attempted to resort to what may have been an obvious mechanical expedient, that is, weaving a wire screen with diagonal woof and warp wires, the result of which, had it been obtained, would obviously have been desirable, but such insurmountable difficulties were met, that it was apparently necessary to abandon the idea.

Applicant has, however, discovered that even though the warp wires lie in lines parallel to the sides, that if the woof wires are placed at an angle other than a right angle, bracing against distortion will be had, such bracing of course increasing in extent and value as the angularity of the woof wires increases from the usual 90 de-

grees to the warp wires. It is obvious that where a wire screen of such nature is fastened to a rectangular frame that any distortion which tends to lengthen the woof wires would be resisted, and such bracing is satisfactory where 5 sag, as of the edges of a door away from the hinged side, is concerned; but it is not so obvious that the stiffening would be accomplished in the opposite direction. It is found, however, by tests that such stiffening does occur provided the 10 wire screen is properly flat and taut after securing to the frame. Applicant believes that the action set up is that the warp wires so confine the warp wires against lateral displacement at each point of crossing of the wires that, slender as the 15 warp wires are, they are thus made sufficiently short relative to their size as to act in compression to resist the distortion. Be that as it may, the result is a stiffening against compression of the rectangular frame along either of its diagonal 20 axes, a result desirable as in window screens.

Applicant has further found that it is possible to weave a wire screen of the above nature in a usual type of machinery adapted to this purpose by shifting the throw of the shuttles from a 25 true right angle to an angle deviating from such right angle as much as 15 or 20 degrees, or possibly even more, the limit of such deviation which may eventually be made by skilled mechanics obviously not having yet been determined. 30

The means by which the foregoing and other objects are accomplished and the method of their accomplishment will be understood from the following specification on reference to the accompanying drawing, in which— 35

Fig. 1 is a face view of a strip of screen-wire woven in accordance with my invention;

Fig. 2 a similar view showing increased angularity of the transverse wires; and

Fig. 3 is a face view of a screen door making 40 use of screen-wire woven in accordance with the showing of Fig. 1.

Referring now to the drawing, in which the various parts are indicated by numerals, 10 are the warp wires spaced uniformly apart and 45 lying parallel to the sides of the strip, and 11 the woof wires disposed at an angle other than a right angle, transversely across the strip, these wires preferably being uniformly spaced and preferably also at the same spacing as the warp 50 wires. As shown in Fig. 1 the woof wires make an angle of about 7½ degrees away from a true ninety degrees to the warp wires, this angle being believed to represent substantially a minimum angle which these wires may have and yet be 55

effective. It is believed, however, that a greater angle than there shown is preferable, such an angle being shown in Fig. 2.

In Fig. 3 a typical screen door is shown, 15 being the side frames, 16 and 17 top and bottom frames and 18 an intermediate cross frame. 19 are hinges and 20 a handle. 21 and 22 are respectively the warp and woof wires. The wire screens form web portions enclosed by the frame members 15, 16 and 18 and the frame members 15, 17 and 18 respectively. The peripheral edges of the webs are covered as by strips 23, which strips may cooperate with the frame members to secure the webs, or may serve to cover the web edges after they have been secured by any of the methods such as are usually employed or may be found desirable for such purposes.

I claim:

1. A fine mesh screen woven from thread like

wire, the warp strands extending continuously along lines parallel to the length of said screen, and the woof wires extending continuously along lines which are parallel and deviate a substantial amount from a ninety degree angle with said woof wires, the warp and woof wires being interwoven but otherwise not deviating from substantially straight lines. 5

2. A fine mesh screen woven from thread like wire, the warp strands extending continuously 10 along lines parallel to the length of said screen and the woof wires extending continuously along lines which are parallel and deviate in excess of five degrees from a ninety degree angle with said warp wires, the warp and woof wires being interwoven, but otherwise not deviating from substantially straight lines. 15

ELDRIDGE P. DOUGLASS.
